CLAIM

The ornamental design for a handle for refrigeration appliance, as shown and described.

DESCRIPTION

FIG. 1 is a perspective view of a handle for refrigeration appliance shown in environmental use;

FIG. 2 is a front view of the handle for refrigeration appliance shown in a second environmental use;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front right side front perspective view thereof;

FIG. 9 is a front left side front perspective view thereof;

FIG. 10 is a perspective view of the handle for refrigeration appliance shown in a third environmental use;

FIG. 11 is a perspective view of the handle for refrigeration appliance shown in a fourth environmental use;

FIG. 12 is a perspective view of the handle for refrigeration appliance shown in a fifth environmental use; and,

FIG. 13 is a perspective view of the handle for refrigeration appliance shown in a sixth environmental use.
The broken lines shown represent unclaimed subject matter and form no part of the claimed design. The dash-dot-dash broken lines represent an unclaimed boundary that forms no part of the claimed design.**1 Claim, 12 Drawing Sheets**(56)
